HYDRAULIC ACTUATING MECHANISM FOR MACHINING IMPLEMENTS

Rolland G. Hall, Yalesville, Conn., and Stewart M. Hill, Sherrill, N. Y., assignors to R. Wallace & Sons Manufacturing Company, Wallingford, Conn., a corporation

Original application July 10, 1948, Serial No. 38,066. Divided and this application March 11, 1950, Serial No. 149,126

11 Claims. (Cl. 51—233)

1

This invention relates to apparatus for finishing opposite surfaces or edges of manufactured articles, and more especially, though not exclusively, to apparatus for trimming and/or buffing the opposite edges of table flatware, such as the customarily butt-joined side edges of knife handles, for instance.

This application is a division of our co-pending application Serial No. 38,066, filed July 10, 1948, which issued as Patent No. 2,576,781 on November 27, 1951.

It is the primary aim and object of the present invention to provide apparatus of this type which will automatically perform simultaneously on a large number of identical articles, such as knife handles, for instance, and which has operating cycles of predetermined duration that are started on momentary manipulation by an operator of a control element of the apparatus.

It is another object of the present invention to provide apparatus of this type in which during an operating cycle thereof the work to be abraded is first moved from a retracted position into operative engagement with oppositely spinning abrading or operating wheels, is then repeatedly reciprocated while remaining in operative engagement with the operating wheels, and is finally returned to retracted position for removal from the apparatus without interference from the spinning wheels.

It is another object of the present invention to provide in apparatus of this type for movement of the work to be operated on in transverse directions between the fast spinning operating wheels, so as to obtain optimum performance of these wheels on the work during an operating cycle of minimum duration.

It is another important object of the present invention to operate the present apparatus principally hydraulically for attaining simplicity of construction of the apparatus, and accomplishing its efficient operation with a minimum number of movable parts and a minimum of wear between the parts.

The above and other objects, features and advantages of the present invention will be more fully understood from the following description considered in connection with the accompanying illustrative drawings.

In the drawings:

Fig. 1 is a front elevation of apparatus embodying the present invention;

Fig. 2 is a side elevation, partly in section, of the apparatus, as viewed in the direction of the arrow 2 in Fig. 1;

2

Figs. 3 and 4 are vertical sections through the apparatus, taken substantially on the lines 3—3 and 4—4, respectively, of Fig. 1;

Fig. 5 is a fragmentary section through the apparatus, taken substantially on the line 5—5 of Fig. 4;

Fig. 6 is a fragmentary section taken on the line 6—6 of Fig. 1;

Fig. 7 shows diagrammatically, in side elevation, certain cooperating parts of the apparatus shown in Fig. 3;

Fig. 8 is a plan view of the parts shown in Fig. 7;

Figs. 9 and 10 are views similar to Fig. 7, but showing the parts in different operating positions; and

Fig. 11 is a hydraulic diagram of certain fluid pressure operated devices of the present apparatus.

Briefly, the instant apparatus is adapted to perform, by way of example, on the opposite sides *s* of hollow knife handles *k* (Fig. 4) which are customarily formed of complementary halves that are soldered at their meeting side edges. In order to render the soldered seams on the finished knife handles to all intents and purposes invisible, they are subjected first to a trimming operation and then to a buffing operation. In this connection, it may be stated in advance that the present apparatus is so constructed as to be adaptable for trimming operation or for buffing operation, or both.

The instant apparatus comprises a base frame 30 which is in the form of a housing having a front wall 32, side walls 34, and a rear wall 36 which leaves an opening 38 in the rear of the frame for ready access to the interior thereof. The front and rear walls 32 and 36 are lined at the top with angles 40 (Figs. 3 and 4) on which is mounted in any suitable manner a platform 42. The side walls 34 of the base frame 30 may also be provided at the top with inwardly extending flanges 44 (Fig. 5) which serve as additional mountings for the platform 42. Mounted in and on the base frame 30 are, as hereinafter described, the operating wheels A and their respective drives B (Figs. 3, 4 and 5). Bolted at 50, or otherwise secured, to the opposite side walls 34 of the base frame 30 are standards 52, respectively, which are joined at the top by a brace 54 in the form of a plate that may be connected with the standards 52 by angles 56 (Figs. 4 and 6). Mounted on the braced standards 52 are, as hereinafter described, a work carrier C (Figs. 1 and 4), carrier operating devices D (Figs. 1 and 4), controls E

for the operating wheels (Fig. 2) and a hydraulic control system F (Fig. 1).

Operating wheels A

As mentioned above, the operating wheels 60 (Figs. 5 and 6) may be either trimming wheels or buffing wheels. Each of these wheels 60 comprises a multiplicity of fabric disks which are mounted on a shaft 62, and are preferably cemented together in their side-by-side relation so as to constitute a fairly rigid wheel. If the wheels 60 are to be used for trimming purposes, their peripheries are preferably coated with a grinding compound which lasts for a considerable number of trimming cycles of the apparatus before re-coating is required. If the wheels 60 are to be used for buffing purposes, there is applied a buffing compound to their peripheries preferably at the start of each buffing cycle of the apparatus.

Journalized in suitable bearing brackets 70 on the base frame 30 are two counter shafts 72 (Figs. 5 and 6), each of which carries near its ends arms 74 that extend through transverse slots 76 in the platform 42 of the base frame 30 (Figs. 3 and 5). The arms 74 on each shaft 72, together with removably mounted caps 78 thereon, provide spaced journal bearings for the shaft 62 of an operating wheel 60. The shafts 72 are rocked in opposite directions so as to swing the operating wheels 60, in the course of their performance, to and from each other in a manner and by means hereinafter described. The peripheries of the wheels 60 extend into the interior of the base frame 30 through a cutout 41 in the platform 42, said cutout 41 being of sufficient width (Fig. 4) to permit the abovementioned swinging motions of the wheels 60. Since the wheels 60 perform an abrading operation regardless of whether they are used for trimming or for buffing, there is provided underneath these wheels pan 80 (Figs. 5 and 6), which is suitably secured to the platform 42, and receives all waste matter dropping from the work and from the wheels 60. The pan 80 has at the rear of the apparatus an outlet 82 which may, through a suitable conduit (not shown), communicate with any conventional suction device for drawing the accumulated waste matter from the pan 80. Suitably hinged at 84 on the platform 42 are guards 86 over the exposed peripheries of the wheels 60 (Fig. 4), these guards serving not only to keep the operator's hands from the wheels 60, but also to direct all waste matter from the work and operating wheels into the pan 80 provided therefor.

Wheel drives B

Two opposed ends of the shafts 62 of the operating wheels 60 extend beyond the adjacent sides of the base frame 30 and there carry pulleys 90, respectively (Fig. 1). The pulley 90' on the rear wheel 60' (Figs. 4 and 5) is drivingly connected by belts 92 with a pulley 94 on the shaft 96 of an electric motor 98 which is suitably mounted on a bracket 100 that is, in turn, mounted for swinging movement at 102 in a bearing bracket 104 on the front wall 32 of the base frame 30 (Fig. 4). The bracket 100 is provided with an upward extension 106 in which is swivelled the shank 108 of a nut 110 with which a spindle 112 is in threaded engagement. The spindle 112 has any conventional universal mounting in a bracket 113 on the rear wall 36 of the base frame 30, and carries a hand wheel 114. Thus, the tension of the belts 92 may be regulated by turning the hand wheel 114 in the proper direction and, in

consequence, swinging the motor-carrying bracket 100 on its pivot axis 102. The pulley 90'' on the front wheel 60'' is drivingly connected by belts 120 with a pulley 122 on the shaft 124 of another electric motor 126 which, as shown in Fig. 3, is carried by a mounting bracket 128, journaled at 130 in a bearing bracket 132 on the rear wall 36 of the base frame 30. Swivelled in an upward extension 134 of the mounting bracket 128 is the shank 135 of a nut 136 which is in threaded engagement with a spindle 138 that has any conventional universal mounting in a bracket 140 on the rear wall 36 of the base frame 30 and carries a hand wheel 142, the latter to be manipulated for regulating the tension of the belts 120, as will be readily understood. Thus, the wheels 60 are individually driven from their respective motors 98 and 126, in opposite directions, and more particularly in the direction of the arrows 146 and 148, respectively, in Fig. 4.

Work carrier C

Referring now more particularly to Fig. 1, the work carrier comprises, in the present instance, a vertically reciprocating frame 150 and an oscillatory frame 152. The reciprocating frame 150 comprises opposite sliding brackets 154 and 156 and connecting cross bars 158. The brackets 154 and 156 are slideable on vertical guide posts 155 and 157, respectively, which are mounted on the adjacent standards 52, respectively, through intermedium of mounting brackets 160 (Figs. 1 and 3). Thus, the sliding brackets 154, 156 and the connecting cross bars 158 form a single unit which is vertically reciprocable on the guide posts 155 and 157.

The oscillatory frame 152 comprises side members 162 and connecting cross bars 164, which together form a single unit. The side members 162 are received for sliding movement on the cross bars 158 of the reciprocating frame 150, thus permitting oscillation of the frame 152 on the other frame 150 transversely of the direction of reciprocation of the latter frame.

Preferably, there are interposed between the slides 154 and 156 and the adjacent brackets 160, respectively, bellows 168 of rubber or the like which surround the guide posts 155 and 157, respectively, and contract and expand on reciprocation of the frame 150, as will be readily understood. These bellows 168 protect the guide posts 155 and 157 from dust and other foreign matter. The length of the guide post 155 between the later lugs 170 of the slide 154 is also protected from dust and other foreign matter by a sleeve 172 which surrounds post 155 and is interposed between the lugs 170 in the manner best shown in Fig. 1. Those portions of the cross bars 158 of the frame 150 on which the side members 162 of the oscillatory frame 152 oscillate, are preferably also protected from dust and other foreign matter by contractable and expandable bellows 174 which are suitably anchored with their ends on the cross bars 158 and on the adjacent side members 162, respectively.

The present apparatus is also equipped with one or more detachable work racks 180 (Fig. 4). The work rack 180 is in the form of a U-shaped bar having opposite legs 182 and a connecting yoke 184. The legs 182 of the work rack are provided with elongated slots 186 (Fig. 4) by means of which the work rack is suspended from headed pins 188 on the lower ends of the side members 162 of the oscillatory frame 152, all as shown more clearly in our aforesaid co-pend-

Fig. application Serial No. 38,066. Suitably secured in the yoke 184 of the work rack 180 are a multiplicity of blades 190 which serve as holders for the knife handles *k* to be operated on. More particularly, the knife handles are inserted over the blades 190 (Fig. 4) and are held thereon in upright position. When suspended from the oscillatory frame 152, as described, the work rack 180 is located in the median vertical plane between the wheels 60 as shown in Fig. 4, so that the knife handles *k* on the work rack will be evenly contacted on opposite sides by the operating wheels 60 on vertical reciprocation of the work rack with the frames 150 and 152.

Operating devices *D* for work carrier

Referring now to Figs. 1 and 4, there is mounted at 192 on the plate 54 between the standards 52 a hydraulic cylinder 194 in which is slidable a double-acting piston 195 (Fig. 11) the rod 196 of which is connected at 198 with a bracket 200 (Fig. 4) which is carried by the cross bars 158 of the frame 150, and serves to impart the reciprocatory motion of the piston 195 in the "work-rack" cylinder 194 to the frame 150.

The prime mover for the oscillation of the frame 152 is an hydraulic motor 202 (Figs. 4 and 6) which is carried by a housing 204 that is, in turn, mounted in any suitable manner on the plate 54 between the standards 52. The hydraulic motor 202 is of a well known type and requires no detailed disclosure. For the present purpose, it is sufficient to understand that the drive shaft 206 of the motor 202 turns in one direction on the passage of a liquid under pressure through the motor. The housing 204 is closed at its open front by a cover 208, and houses a gear 210 (Fig. 6) which is mounted on the motor shaft 206 and is in permanent mesh with another gear 212 on a shaft 214. Shaft 214 is journaled in the housing 204 and cover 208, and carries externally of the housing 204 a disk 216 having a crank pin 218 which is received in a vertical groove 220 in the rear of the side member 162' of the oscillatory frame 152. Thus, the frame 152 and, hence, also the work rack 180 thereon will, on operation of the hydraulic motor 202, be oscillated on the frame 150, and such oscillation of the frame 152 may take place uninterrupted during reciprocation of the other frame 150.

Controls *E* for operating wheels

Referring now more particularly to Figs. 1 and 2, the rock shafts 72 of the operating wheels 60 have extensions 232 beyond one side of the base frame 30 and there carry arms 234, respectively, which are provided at adjacent ends with followers 236, respectively, adapted to cooperate with master cams 238, respectively. The opposite ends of the arms 234 are pivotally connected at 240 with an extension 242 on a cylinder 244 and a piston rod 246, respectively. Rod 246 is carried by a double-acting piston in the cylinder 244, the opposite ends of which communicate with a source of liquid under pressure through conduits 248 and 250, respectively. When liquid under pressure is admitted through conduit 250 into the right-hand end of the cylinder 244, as viewed in Fig. 2, the piston therein is forced to the left, with the result that the lower ends of the arms 234 are forced apart and the followers 236 on the other ends of the arms 234 are forced into engagement with their respective master cams 238. Conversely, the followers 236 on the

arms 234 are disengaged from their respective master cams 238 when liquid under pressure is admitted through conduit 248.

The master cams 238 are accurately positioned on dowel pins 251 on opposite slides 252 and 254, respectively, and are held thereon by screws 253 (Fig. 2). The slides 252 and 254 are guided for movement to and from each other in a horizontal dovetail groove 256 in a slide 258 which is, in turn, guided for vertical movement in a dovetail groove 260 in the sliding bracket 154 of the reciprocating frame 150 (Figs. 1 and 2). The cam-carrying slides 252 and 254 are in threaded engagement with oppositely threaded lengths 262 and 264, respectively, of a spindle 266 which is suitably journaled in forwardly projecting lugs 268 of the vertical slide 258 and carries at one end a hand wheel 270 with which to turn the spindle 266 and thereby adjust the spacing of the master cams 238 in accordance with the width of the knife handles to be operated on by the operating wheels 60. The vertical slide 258 is in threaded engagement with a spindle 272 which is held axially immovable in a projecting lug 274 on the adjacent bracket 154 and carries thereabove a hand wheel 276 with which to turn the spindle 272 and thereby adjust the master cams 238 in correct vertical position.

The active faces 280 of the master cams 238 are machined so that intermediate lengths thereof, each corresponding to the length of a knife handle to be operated on by the wheels 60, together have the correct side contour of this knife handle, and the master cams 238 are so adjusted, through manipulation of the hand wheels 270 and 276, that the correct contour portions of these master cams cooperate with the followers 236 on the arms 234 when the corresponding contour portions of the knife handles on the mounted work rack 180 are in operative engagement with the wheels 60. Thus, the wheels 60, be they trimming or buffing wheels, are on reciprocation of the work between the wheels 60, positively moved to and from each other in such manner that their peripheries follow the correct contour of the work, thereby preventing excessive abrading of the knife handles, and even correcting the contours of the latter where slightly off.

Hydraulic control system *F*

The heretofore mentioned hydraulically operated devices 194, 202 and 244 require for their operation a liquid such as oil, which is put under pressure in a manner hereinafter described by a pump 320 (Fig. 11) that is driven by an electric motor 322 (Fig. 2) which is mounted on the bottom of the base frame 30. The apparatus further comprises an electric fan motor 324 (Fig. 11) which is used in conjunction with a cooler 326 in which the hot oil is on its circuitous path through the apparatus effectively cooled so as to preserve its maximum operating efficiency. The apparatus further comprises a solenoid-operated valve 330 (Fig. 11) which is mounted on the plate 54 between the standards 52, and is preferably enclosed in a cover 334 (Fig. 1). The solenoid valve 330 is one of several controls for the admission of oil under pressure to, or its interception from, the work-rack cylinder 194. Solenoid valve 330 has windings 336 and 338 (Fig. 11).

To start the apparatus, the operator connects the pump motor 322 and fan motor 324 with an electric power source in any suitable manner or

in the manner disclosed in our aforesaid pending application Serial No. 38,066, thereby building up oil under pressure in the various oil lines to be described in the apparatus, before the wheel motors 98 and 126 are permitted to run and before the work is permitted to come into operative engagement with the wheels 60. Next, the wheel motors 98 and 126 may be connected with an electric power source in any suitable manner.

At this stage in an initial operating cycle of the apparatus, the pump motor 322, fan motor 324 and the wheel motors 98 and 126 are operating, but the loaded work rack 180 in the apparatus is still in the raised position shown in Fig. 4. To cause the work rack 180 to descend at the beginning of an abrading cycle of the apparatus, the circuit of the winding 336 of the solenoid valve 330 is closed in any suitable manner or in the manner disclosed in our aforesaid co-pending application Serial No. 38,066. Energization of the winding 336 causes a shift of the solenoid valve 330 from a neutral position to be described into the full-line position shown in Fig. 11, in which the same is conditioned for power reciprocation of the piston 195 in the work-rack cylinder 194 in a manner hereinafter described. The subsequent reversal at the end of each stroke of the piston 195 in the work-rack cylinder 194 is under the control of a pilot valve 640 which is operated by the reciprocating frame 150 in a manner hereinafter described. At the end of an abrading cycle of the apparatus, the circuit of the winding 336 of the solenoid valve 330 is opened, and the circuit of the winding 338 of the same valve is closed, in any suitable manner or in the manner disclosed in our aforesaid co-pending application Serial No. 38,066. Energization of the solenoid winding 338 will cause a shift of the solenoid valve 330 into a position, to be described, in which it will effect the ascent of the work rack 180 to its uppermost or home position in which it will remain, without being oscillated, until the next operating cycle of the apparatus is started.

On energization of the winding 336 of the solenoid valve 330, the latter is, as previously mentioned, shifted into the full line position shown in Fig. 11, in which it provides communication between conduits 550 and 568, that carry oil under pressure from the pump 320, and a conduit 570 which leads to one end of a control valve 572 in which the admitted oil forces the sliding valve 574 into the full-line end position shown in Fig. 11, against the tendency of a spring 576 to move the valve 574 into the opposite end position. When the valve 574 is shifted into this full-line position, oil under pressure from the pump 320 is immediately admitted to the top end of the work-rack cylinder 194 by way of conduit 550, a conduit 580, a flow control valve 582, conduits 584 and 586, a control valve 588 (assuming at this time full-line position in Fig. 11 for down stroke of work-rack piston 195 as hereinafter described), conduit 590, control valve 572, and conduit 592. Oil under pressure is at the same time admitted to the lower end of the work-rack cylinder 194 by way of conduit 584 and a preferably interposed pressure control valve 594. Inasmuch as the exposed cross-sectional area of the piston 195 in the work-rack cylinder 194 is larger at the top than at the bottom thereof, it stands to reason that the total pressure of the oil against the top face 598 of the piston 195 exceeds the total pressure of the oil against the bottom face 600 thereof, with the

result that the piston 195 descends and carries the work on the rack 180 between the operating wheels 60. The oil in the lower end of the cylinder 194 is, during the descent of the piston 195 therein, by-passed to the top end of the cylinder by way of conduit 584 and interposed valve 594, conduit 586, valve 588, conduit 590, valve 572 and conduit 592.

Simultaneously with the start of the work reciprocation, oil under pressure is also permitted to flow from the pump 320 through the work-oscillating motor 202 by way of the conduits 550 and 580, a conduit 602, a flow control valve 604, a conduit 606, and the motor 202, thence through conduits 608 and 610, solenoid valve 330, and conduits 612, 614 and 566 to an oil reservoir 560 from which the pump 320 draws oil. Thus, the work rack 180 starts to oscillate at the same time it starts to descend on its first work stroke. Simultaneously with the shift of the solenoid valve 330 into the full-line position shown in Fig. 11, oil under pressure from the pump 320 is also admitted to the active side of the wheel pressure cylinder 244 by way of conduit 550, a conduit 620, a flow control valve 622, a conduit 624, a pressure control valve 626, and the flexible hose connection 250. The oil in the opposite side of the same cylinder 244 is then permitted to return to the oil reservoir 560 by way of the flexible hose connection 248, conduit 610, solenoid valve 330, and conduits 612, 614 and 566. Thus, on energization of the winding 336 in each operating cycle of the apparatus, and according shift of the solenoid valve 330 into the full-line position shown in Fig. 11, the cylinders 194 and 244 and the hydraulic motor 202 simultaneously receive oil under pressure, with the result that the work-rack piston 195 will descend for the first time in a cycle, the cylinder 244 and piston therein will bring the operating wheels 60 under the control of the master cams 238, and the hydraulic motor 202 will oscillate the work.

Suitably mounted on vertically adjustable brackets 632 and 633 on the slide 156 of the reciprocating frame 150 (Fig. 3) are two blocks 634, respectively, having projecting lugs 636 and 638, respectively, which are adapted to operate the previously mentioned pilot valve 640 (see also Figs. 7 to 10). The brackets 632 and 633 are slidable in a dove-tail groove 635 in the slide 156 (Fig. 3) and are in threaded engagement with axially immovable spindles 637 and 639, respectively, on the slide 156, said spindles 637 and 639 having knobs 641 and 643, respectively, with which to turn said spindles and thereby adjust the vertical position of the respective brackets 632 and 633. The pilot valve 640 comprises a casing 642 (Fig. 11) and a rotary valve element 644 therein. The valve element 642 extends to the outside of the valve casing 640 and there carries a valve actuator 646 having angularly spaced fingers 648 and 650 which are also spaced horizontally from each other as shown in Fig. 8. The finger 648 of the valve actuator 646 is in operative alignment with the lower lug 638, while the other finger 650 of the valve actuator is in operative alignment with the upper lug 636. As previously mentioned, the pilot valve 640 is adapted to control the flow of oil to and from the top and bottom of the work-rack cylinder 194 so as to reverse the piston 195 therein at the end of each down or upstroke thereof, and this control is operative throughout the time of reciprocation of the work in an operating cycle of the apparatus. The vertical adjustability of the lugs 636 and 638 in

the apparatus also affords a convenient means not only to regulate the stroke of the piston 195 in the work-rack cylinder 194 for the reciprocation of the work, but also to confine the reciprocation of the piston 195 to different regions within the work-rack cylinder 194. Thus, by properly adjusting the lugs 636 and 638, the work will, after its initial descent from uppermost position, be reciprocated through partial strokes of such length that the work will remain in operative engagement with the operating wheels 60 throughout its reciprocation, and will at the end of an abrading cycle of the apparatus be raised to its uppermost position in which it is out of operative engagement with the wheels 60 and may be removed from the apparatus. Also, the described adjustability of the lugs 636 and 638 adapts the apparatus for trimming or buffing knife handles of different length, as will be readily understood.

The angular position of the valve actuator 646 and, hence, of the rotary element 644 in the pilot valve 640 depends solely on the preceding downward or upward stroke of the reciprocatory frame 150. Thus, when the work-carrying frame 150 descends, the upper lug 636 thereon will, near the lower limit of the down stroke of said frame as determined by the adjustment of lug 636, engage the finger 650 of the valve actuator 646 and turn the latter from the position shown in Fig. 7 into that shown in Fig. 9, in which finger 650 is out of the path of the lug 638, and the other finger 648 is in the path of the other lug 638 on the following upstroke of the frame 150. The lug 638 will engage finger 648 of the valve actuator 646, and turn the latter back to the position shown in Fig. 10, when the work-carrying frame 150 is near the upper limit of its following partial upstroke as determined by the adjustment of the lug 638. In the position of the pilot valve 640 as shown in Figs. 7, 9 and 11, the same provides communication between the pump 320 and the left hand end of valve 588 (Fig. 11) by way of conduit 550, a passage 660 in the valve element 644 and a conduit 662. The right hand end of valve 588 is then exhausted by way of conduit 664, another passage 661 through the rotary element 644 in the pilot valve 640, a conduit 670, and the conduits 614 and 566. In consequence of the described admittance of oil under pressure to the valves 588, the latter assumes the full-line position shown in Fig. 11, in which oil under pressure is admitted to the top end of the work-rack cylinder 194, as previously described. Hence, the work-rack piston 195 will, in an operating cycle of the apparatus, descend after each partial upstroke thereof, every time the pilot valve 640 is shifted into the position shown in Figs. 7 and 11, except when the latter is thus shifted for the last time in each operating cycle, as will become obvious hereinafter. When the lug 636 shifts the pilot valve 640 into the position shown in Fig. 9 on each descent of the work-carrying frame 150, the valve element 644 of the pilot valve will intercept communication between the conduits 550 and 662, and instead provide communication between conduit 550 and conduit 664 which leads to the right hand end of the valve 588 as viewed in Fig. 11. Admittance of oil under pressure to the right hand end of the valve 588 results in a shift of the valve element 686 therein from the full-line position into the dot-and-dash line position. The left hand end of the valve 588 is then exhausted by way of conduit 662, passage 661 in the rotary element 644 of the pilot valve 640, and conduits 670, 614 and 566. The valve element 686 of valve

588 now being in the dot-and-dash line position in Fig. 11, the same permits the exhaust of the top end of the work-rack cylinder 194, resulting in an upstroke of the piston 195 therein because the lower end of the cylinder remains subjected to oil under pressure. The upper end of the work-rack cylinder 194 is then exhausted by way of conduit 592, valve 572, conduit 593, valve 588, and conduit 566. When the ascending frame 150 approaches the adjusted upper limit of its partial stroke, the lug 638 engages the aligned finger 648 of the valve actuator 646 and turns the pilot valve 640 back to the position shown in Figs. 7 and 11, resulting in the next descent of the work. The work-rack piston 195, and, hence, the frames 150 and 152 as well as the work rack 180, are thus reciprocated until the winding 336 of the solenoid valve 330 is deenergized and the winding 338 thereof is energized. When the winding 338 of the solenoid valve 330 is energized, the solenoid valve 330 is shifted into the dot-and-dash line position shown in Fig. 11, in which oil under pressure in the conduit 568 is admitted through the valve 330 and the conduits 610 and 608 to the work-oscillating motor 202, thereby immediately locking the latter hydraulically. Oil under pressure in the conduit 610 is then also admitted through the hose connection 248 to the wheel pressure cylinder 244 for effecting separation of the operating wheels 60 and according disengagement of the followers on the arms 234 from their respective master cams 238. The other side of the wheel-pressure cylinder 244 is then exhausted by way of the hose connection 250, valve 626, a conduit 672 and conduit 566, the spring-urged valve element 627 in the valve 626 being then subjected at the bottom to oil under pressure in the conduit 610 and, in consequence, raised sufficiently to provide communication between the hose connection 250 and the conduit 672. Energization of the winding 338 of the solenoid valve 330 at the end of an abrading or operating cycle of the apparatus and the corresponding shift of the solenoid valve 330 into the dot-and-dash line position shown in Fig. 11, result also in the exhaust of the left hand end of the valve 572, so that the valve element 574 therein may, under the force of the spring 576 move into the dot-and-dash line position in Fig. 11. Valve 572 is thus exhausted by way of conduit 578, solenoid valve 330, and conduits 612, 614 and 566. Valve 572 now assuming the dot-and-dash line position shown in Fig. 11, the top end of the work-rack cylinder 194 is exhausted by way of conduit 592, valve 572, a conduit 678 and conduit 566. The lower end of the cylinder 194 is subjected to oil under pressure as long as the pump 320 operates, wherefore the work-rack piston 195 and parts connected therewith are returned to their uppermost position at the end of each operating cycle of the apparatus. Should the operator stop the apparatus for any length of time, i. e. by also stopping the pump motor 322, the oil in the various lines supplied by the pump 320 will then be no longer under pressure, with the result that the valve element 680 in the valve 588 is spring-urged into a position in which it blocks conduit 584, whereby the oil in the lower end of the work rack cylinder 194 becomes locked therein and retains the piston 195 in its uppermost position while the apparatus is stopped completely.

The sliding valve element 686 in the solenoid valve 330 is, whenever both windings 336 and 338 thereof are deenergized, forced by balanced springs (not shown) into the before-mentioned

neutral position in which the lands 670 of the valve element 686 block the adjacent ends of the conduits 610 and 570, respectively, and thus intercept communication between these conduits and the conduit 568 which is in open communication with the pump 320.

Résumé of operation

Assuming that the present apparatus is at a complete standstill and that a loaded work rack 180 is suspended from the oscillatory frame 152 in the manner best shown in Fig. 4, the operator will then initiate an operating cycle by first closing the circuit of the pump motor 322. Operation of the pump 320 results in the build-up of oil under pressure in the various oil lines that lead to the hydraulic devices of the apparatus. However, these oil lines are at this initial stage in an operating cycle effectively blocked from their respective hydraulic devices so that the continuously flowing oil from the pump is at this time returned to the oil reservoir 560 past a check valve 700 and through a conduit 702. At this time also the circuit of the motor 324 for the oil cooler 326 is closed. Next, the circuits of the wheel motors 98 and 126 are closed, whereupon the circuit of the winding 336 of the solenoid valve 330 is closed. Immediately on closure of the circuit of the winding 336 of the solenoid valve 330, the latter is shifted into the full-line position shown in Fig. 11, in which the same effects swinging movement of the operating wheels 60 and their follower arms 234 into operative relation with the master cams 238, and further effects reciprocation and oscillation of the work to permit the operating wheels 60 to perform the desired abrading operation on the opposite side edges of the knife handles while the same remain in operative engagement with the wheels 60. More particularly, the solenoid valve 330 will, when in the full-line position shown in Fig. 11, effect a shift of the control valve 572 into the full-line position, in which oil under pressure is admitted through the latter to the top end of the work-rack cylinder 194 to effect the first and full down stroke of the work from uppermost position. The solenoid valve 330 will then also provide communication between the exhaust conduits 608 and 610 of the work oscillating motor 202 and the exhaust conduits 612, 614 and 566, thereby unlocking the motor 202 and permitting the same to be operated by oil under pressure flowing through the conduits 550, 580 and 602, flow-control valve 604 and conduit 606 (Fig. 11). The solenoid valve 330 will then also permit the exhaust of the right hand side of the wheel pressure cylinder 244 (Fig. 11), with the result that oil under pressure will now be admitted into the other side of the cylinder 244 and the follower arms 234 of the operating wheels 60 will be brought into operative relation with the master cams 238. The lower end of the work-rack cylinder 194 is permanently subjected to oil under pressure from the pump 320 as long as the latter operates, as has been previously explained. However, on initial admission of oil under pressure to the upper end of the cylinder 194, in consequence of the shift of the valve 572 into the full-line position shown in Fig. 11, the oil displaced from the lower end of the cylinder 194 by the descending piston 195 therein is bypassed to the top end of the same cylinder through conduit 584 with the interposed valve 594, conduit 586, valve 588, conduit 590, valve 572, and conduit 592.

The pilot valve 640 assumes the position shown in Figs. 7 and 11 when the frame 150 with the work thereon starts to descend from uppermost position for the first and only time in an operating cycle of the apparatus. This is due to the fact that the pilot valve has been shifted into this position by the frame 150 on its ascent into uppermost position at the end of the preceding cycle of operation of the apparatus. Toward the end 10 of the initial and full downward stroke of the frame 150, the lug 636 thereon will shift the pilot valve 640 from the position shown in Fig. 7 into the position shown in Fig. 9, in which the same admits oil under pressure from the conduit 550 through the conduit 664 into the right hand end of the valve 588, causing thereby a shift of the latter from the full-line position into the dot-and-dash line position shown in Fig. 11, in which the top end of the work-rack cylinder 194 is permitted to exhaust by way of conduit 592, valve 572, conduit 590, valve 588, and conduit 566. The work-rack piston 195 will then reverse its stroke and move upwardly, this by virtue of the fact that the lower end of the work-rack cylinder 194 is 15 continuously subjected to oil under pressure from the pump 320. When the frame 150 then nears the adjusted limit of its partial upstroke, the lug 638 thereon will engage the finger 648 of the valve actuator 646 and turn the pilot valve 640 back into the position shown in Figs. 7 and 11, in which the same effects a renewed down stroke of the work-rack piston 195, as will be readily understood. Thus, the work will continue to 20 reciprocate and oscillate while remaining in operative engagement with the wheels 60, until the circuit of the winding 336 of the solenoid valve 330 is opened and the circuit of the winding 338 thereof is closed. Closure of the circuit of the winding 338 causes a shift of the solenoid valve 330 from the full-line position into the dot-and-dash line position (Fig. 11) in which conduit 570 is exhausted by way of valve 330 and the conduits 612, 614 and 566, with the result that valve element 574 in the valve 572 is spring-urged into the dot-and-dash line position (Fig. 11) in which the top end of the work-rack cylinder 194 is permitted to exhaust by way of conduit 592, valve 572, and conduits 678 and 566. When in the dot-and-dash line position, the solenoid valve 330 also provides communication between the conduit 568 that carries oil under pressure, and the conduit 610 and branch conduit 608, thereby causing the work-oscillating motor 202 to become hydraulically locked, and causing the wheel pressure cylinder 244 and piston therein to withdraw the follower arms 234 of the operating wheels 60 from their respective master cams 238, all as previously described in detail.

While we have shown and described a preferred embodiment of our invention, it will be understood that various changes may be made in the present invention without departing from the underlying idea or principles of the invention within the scope of the appended claims.

Having thus described our invention, what we claim and desire to secure by Letters Patent, is:

1. Apparatus of the character described, comprising a reciprocatory carrier, a stationary cylinder, a double-acting piston slideable in said cylinder, said piston having one face fully exposed in said cylinder and having its opposite face only partially exposed, said opposite face having a projecting rod connected with said carrier for reciprocating the latter, a conduit providing communication between that cylinder side in which said

other piston face is exposed and a source of fluid under pressure, a valve casing having an exhaust port and first and second ports in communication with said conduit and the other cylinder side, respectively, a plunger slidable in said casing into first and second positions in which to provide communication between said first and second ports and between said second and exhaust ports, respectively, and a device actuated by the reciprocating carrier at the ends of strokes thereof toward and away from said cylinder for shifting said plunger into said first and second positions, respectively, said device comprising hydraulic valve means.

2. Apparatus as set forth in claim 1, in which said device comprises a stationary valve having first, second and third ports in communication with said conduit and the opposite ends, respectively, of said valve casing, and a valve element therein shiftable into positions in which to provide communication between said first and second ports and between said first and third ports, respectively, and two elements on said carrier spaced in the direction of reciprocation of the latter and adapted to shift said valve element into said positions, respectively, at the ends of consecutive strokes, respectively, of said carrier.

3. Apparatus as set forth in claim 1, in which said device comprises a stationary valve having first, second and third ports in communication with said conduit and the opposite ends, respectively, of said valve casing, and a valve element therein shiftable into positions in which to provide communication between said first and second ports and between said first and third ports, respectively, and two elements on said carrier spaced in the direction of reciprocation of the latter and adapted to shift said valve element into said positions, respectively, at the ends of consecutive strokes, respectively, of said carrier, one of said elements being adjustable on said carrier in the direction of reciprocation of the latter to vary the stroke of said carrier.

4. Apparatus of the character described, comprising a reciprocatory carrier, a stationary cylinder, a double-acting piston slidable in said cylinder, said piston having one face fully exposed in said cylinder and having its opposite face only partially exposed, said opposite face having a projecting rod connected with said carrier for reciprocating the latter, a conduit providing communication between that cylinder side in which said other piston face is exposed and a source of fluid under pressure, a valve casing having an exhaust port and first and second ports in communication with said conduit and the other cylinder side, respectively, a plunger slidable in said casing into first and second positions in which to provide communication between said first and second ports and between said second and exhaust ports, respectively, a device actuated by the reciprocating carrier after each partial stroke thereof toward, and after each stroke thereof away from, said cylinder for shifting said plunger into said first and second positions, respectively, said device comprising hydraulic valve means and means other than said valve casing for exhausting said other cylinder side.

5. Apparatus as set forth in claim 4, in which said device comprises a stationary valve having first, second and third ports in communication with said conduit and the opposite ends, respectively, of said valve casing, and a valve element therein shiftable into positions in which to pro-

vide communication between said first and second ports and between said first and third ports, respectively, and two elements on said carrier spaced in the direction of reciprocation of the latter and adapted to shift said valve element into said positions, respectively, at the ends of consecutive strokes, respectively, of said carrier.

6. Apparatus as set forth in claim 4, in which said device comprises a stationary valve having first, second and third ports in communication with said conduit and the opposite ends, respectively, of said valve casing, and a valve element therein shiftable into positions in which to provide communication between said first and second ports and between said first and third ports, respectively, and two elements on said carrier spaced in the direction of reciprocation of the latter and adapted to shift said valve element into said positions, respectively, at the ends of consecutive strokes, respectively, of said carrier, one of said elements being adjustable on said carrier in the direction of reciprocation of the latter to vary the partial stroke of said carrier.

7. Apparatus as set forth in claim 4, in which said device comprises a stationary valve having first, second and third ports in communication with said conduit and the opposite ends, respectively, of said valve casing, and a valve element therein shiftable into positions in which to provide communication between said first and second ports and between said first and third ports, respectively, and two elements on said carrier spaced in the direction of reciprocation of the latter and adapted to shift said valve element into said positions, respectively, at the ends of consecutive strokes, respectively, of said carrier, said elements being individually adjustable on said carrier in the direction of reciprocation of the latter to vary the partial stroke of said carrier and/or shift the region within which said carrier reciprocates.

8. Apparatus of the character described, comprising a reciprocatory carrier, a stationary cylinder, a double-acting piston slidable in said cylinder, said piston having one face fully exposed in said cylinder and having at its other face a projecting rod connected with said carrier for reciprocating the latter, a first conduit providing communication between that cylinder side in which said other piston face is exposed and a source of fluid under pressure, another conduit branching from said first conduit and leading to the other cylinder side, a valve casing having an exhaust port and being interposed in said branch conduit, a plunger slidable in said casing into first and second positions in which to provide communication through said branch conduit and between said exhaust port and other cylinder side, respectively, a device actuated by said carrier after each partial stroke thereof toward, and after each stroke thereof away from, said cylinder for shifting said plunger into said first and second positions, respectively, another valve having an exhaust port and being also interposed in said branch conduit between said other cylinder side and said valve casing, and a valve element in said valve slidable into first and second positions in which to provide communication through said branch conduit and between said other cylinder side and exhaust port of said other valve, respectively, and another device for sliding said valve element into either of said positions.

9. Apparatus as set forth in claim 8, in which

said valve element is in said second position thereof at one end of said other valve, and said other device comprises means in said other valve yieldingly urging said valve element into said second position, a third valve having an exhaust port and third and fourth ports in communication with said fluid source and said one end of said other valve, respectively, and another valve element in said third valve shiftable into positions in which to provide communication between said third and fourth ports and between said fourth and exhaust ports, respectively, of said third valve.

10. Apparatus as set forth in claim 8, in which said valve element is in said second position thereof at one end of said other valve, and said other device comprises means in said other valve yieldingly urging said valve element into said second position, a third valve having an exhaust port and third and fourth ports in communication with said fluid source and said one end of said other valve, respectively, another valve element in said third valve shiftable into positions in which to provide communication between said third and fourth ports and between said fourth and exhaust ports, respectively, of said third valve, two solenoid windings associated with said other valve element and adapted, when energized, to shift the latter into said positions, respectively, and a separate circuit for each solenoid winding, including a switch for opening and closing said circuit.

11. Apparatus of the character described, comprising a first frame, a second frame mounted on said first frame for oscillation in a certain direction, said first frame being reciprocable transversely of the direction of oscillation of said second frame, a stationary cylinder, a double-acting piston shiftable in said cylinder, said piston having one face fully exposed in said cylinder and having at its other face a projecting rod connected with said first frame for reciprocating the latter, means for oscillating said second frame on said first frame when the latter reciprocates, said means including a fluid motor having an inlet and an outlet, a first conduit providing communication between that cylinder side in which said other piston face is exposed and a source of fluid under pressure, a second conduit branching from said first conduit and leading to the inlet of said fluid motor, a third conduit also branch-
